(57) **CLAIM**

The ornamental design for a “bottle tether,” as shown and described.

DESCRIPTION

FIG. 1 is a isometric perspective view of the bottle tether;
FIG. 2 is a front view of the bottle tether;
FIG. 3 is a back view of the bottle tether;
FIG. 4 is a left view of the bottle tether;
FIG. 5 is a right view of the bottle tether;
FIG. 6 is a top view of the bottle tether;
FIG. 7 is a bottom view of the bottle tether; and,
FIG. 8 is an environmental perspective view including the bottle tether.
The broken lines shown in the drawings represent portions of the bottle tether or environment that form no part of the claimed design.
